UNITED STATES PATENT OFFICE.

WILLIAM McCULLOUGH, OF NEW YORK, N. Y.

GAGE.

SPECIFICATION forming part of Letters Patent No. 270,091, dated January 2, 1883.

Application filed May 11, 1882. (Model.)

To all whom it may concern:

Be it known that I, WILLIAM McCULLOUGH, of the city, county, and State of New York, have invented a new and useful Improvement 5 in Gages, of which the following is a full, clear, and exact description.

My invention seeks to improve that class of gages which are more especially used for gag- 10 ing door-jambs and the edges of doors for the proper setting of the door-hinges, for hanging the door, and for cutting the door and jamb the depth that it is necessary to remove the wood to set the leaves of the hinges flush with the edge of the door and the face of the jamb; 15 and it consists of a suitable stock provided with two marking points or blades (one longer than the other) to be used in combination with a slotted head-block adapted to slide on the stock, the head-block having two gage sur- 20 faces or faces at right angles to the stock, which are the same distance apart that the marking points or blades are, as hereinafter more fully set forth, and pointed out in the claims.

25 I provide the head-block with an ordinary gage-bar to be used for ordinary purposes, and this, in connection with the head-block itself and the main stock, constitutes a further feature of my invention.

30 Reference is to be had to the accompanying drawings, forming a part of this specification, in which similar letters of reference indicate corresponding parts in all the figures.

Figure 1 is a plan view of the under side of 35 my new and improved gage. Fig. 2 is a side elevation of the same, illustrating the manner of using the gage for marking or cutting the edge of a door. Fig. 3 is a similar view, illustrating the manner of using the gage for mark- 40 ing or cutting the jamb of the door-casing; and Fig. 4 is a front elevation of the gage.

A represents the stock, which is by prefer- 45 ence square in cross-section, and may be of any suitable length; and B represents the head- block, which is adapted to slide upon the stock in the ordinary way. The stock is provided with the marking points or blades a and b, the latter being of considerable length, as shown in the drawings, and the head-block B is 50 formed with the slot d, so that the block may be slid upon the stock past the point or blade

b. f f' are the opposite gage surfaces or faces of the head-block B, which are the same dis- tance apart that the marking points or blades a and b are; and C represents the ordinary 55 gage-bar, which slides in the head-block B, and which is provided with the ordinary mark- ing-point, c, the surface g of the head-block serving as its gage surface or face.

D is the thumb-screw for setting the bar C, 60 and E the thumb-screw for setting the head- block B at any desired position upon the stock A.

The distance between the surfaces f and f' of the head-block being exactly equal to the 65 distance between the marking-points a and b, it will be seen that when the surface f is moved to and from the point a the surface f' will be moved an equal distance toward or from the point b, so that the distance between the sur- 70 face f' and the point b will always be exactly equal to the distance between the surface f and the point a, so that a line or mark made with the point b, the surface f' being the gage, will always be the same distance from the ob- 75 ject against which the face f' is placed that a line or mark made with the point a will be from the surface against which the face f is placed as the gage, the head-block remaining in the same position.

In using my improved gage for hanging doors, or for marking or cutting the jamb J, the face f' of the head-block will be placed against the jamb at J', as shown in Fig. 3, and the mark or cut made by the point or blade b. 85 For marking or cutting the edge of the door K the gage will be applied to the door as shown in Fig. 2, the surface or face f being placed against that side of the door the corner of which shuts against the jamb at J', as shown, 90 and the mark or cut made by the point or blade a. By this means it will be seen that the distance from the jamb at J' to the mark made on the jamb will be exactly equal to the distance between the mark on the edge of the 95 door and the side of the door which comes against the jamb, so that when the door is hung the side of the door will come properly against the jamb.

The gage C is used in the ordinary manner. 100 Thus constructed it will be seen that the gage is fitted for a variety of work, and is cheap

and simple, and when used for hanging doors is very accurate and easily set and handled.

Having thus described my invention, I claim as new and desire to secure by Letters Patent—

- 5 1. The combination, with the stock A, provided with the points *a* *b*, the latter being the longest, of the sliding head-block B, provided with the central slot, *d*, and gage surfaces or faces *f* *f'* at right angles to the slot and at the same distance apart that the marking-points *a* *b* of the stock are, substantially as described, and for the purpose set forth.

2. In a gage, the combination of the stock A, provided with two points, *a* and *b*, one of which, *b*, is longer than the other, and the slotted head-block B, adapted to slide on the same, and having two parallel faces, *f* and *f'*, at the same distance apart as the points *a* and *b* of the stock A, with the bar C, provided with one marking-point, *c*, substantially as specified.

WILLIAM McCULLOUGH.
